UNITED STATES PATENT OFFICE.

EDWARD I. FRIEDMAN, OF CHICAGO, ILLINOIS.

CORD-POLISHING MACHINE AND THE LIKE.

1,387,045.

Specification of Letters Patent.

Patented Aug. 9, 1921.

Application filed March 21, 1919. Serial No. 284,152.

To all whom it may concern:

Be it known that I, EDWARD I. FRIEDMAN, a citizen of the United States, residing at Chicago, in the county of Cook and State of Illinois, have invented certain new and useful Improvements in Cord-Polishing Machines and the like, of which the following is a specification.

The present invention has to do with improvements in machines for polishing cords and the like, and will be found of wide applicability and usefulness in this class of work. The features of the present invention are particularly well adapted for use in connection with polishing cords such as gut strings used in stringed instruments such as violins and cellos, in tennis rackets, as belt lacing, etc., but the features of the invention are in nowise limited to this particular or

any other class of service.

I will state, however, by way of illustration that strings such as those previously mentioned are commonly manufactured from guts and in their raw condition are rough and irregular, so that they are required to be polished or smoothed in order to become serviceable for the purposes intended. These strings are also of variable length and size, and, therefore, any machine to become of wide usefulness in this art should be capable of handling or polishing cord of considerable variations in length and size. One of the objects of the present invention is to produce such a machine.

I will also state that it is necessary to polish the cords uniformly on all sides or portions of them in circular fashion, and another object of the present invention is to produce a machine capable of accomplishing this result.

Other objects of the invention are to provide a machine which shall be practically automatic in its operation and so constructed that the cords when delivered from the machine will be highly polished, notwithstanding the fact that in their original condition they were extremely rough.

Other objects and uses of the invention will appear from a detailed description of the same which consists in the features of construction and combinations of parts hereinafter described and claimed.

Referring to the drawings:

Figure 1 shows a plan view of an assembled machine embodying the features of the present invention, the polishing block standing approximately at the middle or central portion of its movement;

Fig. 2 is a detailed cross sectional view taken on the line 2—2 of Fig. 1, looking in the direction of the arrows;

Fig. 3 is a longitudinal vertical section taken on the line 3—3 of Fig. 1, looking in the direction of the arrows;

Fig. 4 is a vertical cross section taken on the line 4—4 of Fig. 1, looking in the direction of the arrows; and

Fig. 5 is a detailed vertical section in fragmentary form taken on the line 5—5 of Fig. 2, looking in the direction of the arrows.

I will first explain that the machine of the present invention is so constructed that the cords may be mounted in rectangular frames or carriers which are then introduced into the machine and travel through it, and the cords are polished and finished during such travel through the machine.

Bearing the foregoing in mind, the machine illustrated in the drawings includes a pan 10 of elongated form which may be supported in any convenient manner, as, for example, by means of the end brackets 11 and 12. The material which is polished off from the cords falls into said pan and collects in the lower central portion 13 thereof whence it may be withdrawn by a suction fan 14 and removed and delivered away from the operator so as to improve the conditions under which the operations are carried on.

In the end portions of the machine there are provided the chain carriers or the like 15 and 16 which travel in unison and serve to carry the cord frames or carriers across the machine during the polishing process. These chain carriers travel over sprocket wheels 17, 18, 19, and 20 in the four corners of the machine, the carrier 15 traveling over the sprockets 17 and 19 and the carrier 16 over the sprockets 18 and 20. The shafts 21 and 22 extend lengthwise of the machine being suitably journaled in the end brackets as is clearly evident particularly from Figs. 3 and 4.

A motor 23 drives the suction fan 14 through the medium of a jack shaft 24, which jack shaft passes centrally under the machine. This jack shaft drives the 5 sprocket 21 through the medium of a chain 25, and by so driving the sprocket shaft 21, the sprocket shaft 23 is also driven since both of said sprocket shafts are connected together by the chain carriers 15 and 16.

10 The chain carrier 15 is fixed in position at one end of the machine, while the chain carrier 16 and its sprockets and the coöperating mechanism presently to be described are adjustably mounted in the other end of the 15 machine, so that they may be set back and forth into different positions according to the length of the cords to be operated on. For this purpose the sprockets 18 and 20 are feather-keyed to their respective shafts 20 21 and 22. A stationary housing 26 is provided at the fixed end of the machine within which housing is journaled a worm or screw shaft 27, as is clearly evident from an examination of Figs. 1 and 3. The chain 25 carrier 15 also travels through this housing and adjacent to the shaft 27. At the adjustable end of the machine, there is a movable housing 28 within which is journaled another worm or screw shaft 29, the construction of which will be clearly evident from Figs. 1, 2, 3, 4 and 5. The chain carrier 16 also travels through the housing 28 at a point adjacent the shaft 29.

The adjustable housing 28 has its end portions resting upon the flanges or seats 30 and 31 of the table, which said seats are provided with tap screw holes 32 and 33 by means of which the housing 28 may be secured in any adjusted position according to 40 the length of the cords to be operated upon.

Each of the cord frames comprises end portions 34 and 35 in conjunction with connecting side walls 36 and 37. Each of the end walls 34 and 35 carries a number of 45 hooks 38 which are journaled therein, so that they can rotate, and said hooks 38 are provided with worm pinions 39 on their outer or protruding ends. The worms 39 at one end of the frame mesh with the worm 50 screw 27, and the worms 39 at the other end of the frame mesh with the worm screw 29. Consequently by rotating said screws 27 and 29, the hooks will be rotated, and by properly proportioning the parts, the hooks will 55 be rotated in unison as the frame travels across the machine. It will be understood that the cords 40 are stretched between the hooks in pairs as is clearly evident from the examination of Figs. 1, 2, 3, and 4.

60 The worms 27 and 29 are caused to rotate in unison by means of a chain 41 passing over sprockets on said worms. The worm 27 is driven from the shaft 24 by means of a chain 42 passing over a sprocket 43 on said 65 shaft and over a sprocket 44 on a stub shaft

45. The stub shaft drives a riser shaft 46 through the medium of the beveled gear pinion 47, the riser shaft in turn driving the worm 27 through the medium of a worm and pinion 48. Thus the worms 27 and 29 are 70 driven in harmony with the shaft 24, and, therefore, also in harmony with the carrier chains 15 and 16.

With the arrangement thus far described, the frames with the cords will be carried 75 through the machine, while the cords are rotated during such travel. I will now describe the mechanism provided for polishing the cords as they go through the machine. For this purpose, I have provided a 80 shoe 49 of width equal to the operating width of the machine, which shoe carries on its lower surface the sand paper or other abrasive material which operates on the cords. As a matter of convenience, the shoe 85 ordinarily carries three different grades of such polishing material, so that as each frame with its cords passes through the machine, it will first be subjected to a coarse abrasive, then to a medium coarse abrasive, 90 and finally to a fine abrasive material.

The shoe 49 is caused to travel back and forth lengthwise of the cords a number of times during the travel of the machine. This is done by the provision of a worm screw 95 50 journaled above the cords in the fixed journal 51 and the movable journal 52, the movable journal 52 being an upward extension from the adjustable housing 28. The shoe 49 is provided with an arm 53 which 100 reaches up to the screw 50 and is engaged thereby, so that by rotating the screw the shoe will be caused to travel back and forth.

The screw carries a beveled gear 51 which is in mesh with upper and lower beveled 105 gears 55 and 56. A riser shaft 57 is driven from the motor shaft 24 through the medium of the beveled gears 58, and said riser shaft carries a clutch block 59 between the beveled gears 55 and 56, so that by shifting said 110 clutch block back and forth it will be possible to cause the same to drive either of the beveled gears, the clutch block being feather-keyed to the shaft 57. In this way, the rotation of the screw shaft 50 can be periodically 115 reversed. This periodical reversal can be effected through the medium of a pair of collars 60 and 61 slidably mounted on the shaft 50, and which collars are connected to a rod 62 which operates the clutch block 59 120 through the medium of a bell crank 63. By properly setting the collars 60 and 61 on the rod 62, said rod will be shifted back and forth so as to automatically reverse the movement of the shoe 49 at the end of the 125 travel in each direction.

I wish to point out the fact that, by the use of the worm shafts 27 and 29, the cords may be caused to rotate any desired number of times on their own axes as they travel 130

across the machine. This will insure a more perfect and complete polishing of each and every portion of the cords than would be secured with a less number of rotations.

5 While I have herein shown and described only a single embodiment of the features of my present invention, still I wish it clearly understood that I do not limit myself to said embodiment except as I may do so in the 10 claims.

I claim:

1. In a machine of the class described, the combination with a main frame, of a pair of chain carriers mounted for carrying movement transversely thereof, a worm screw adjacent to each of said chain carriers, means for driving the worm screws in unison, a polishing shoe adapted for reciprocating motion back and forth between the chain carriers, abrasive material on the lower surface of said shoe, a longitudinally extending worm screw, an operative connection between said screw and shoe aforesaid, a reversal clutch mechanism in conjunction with 15 said screw, means in conjunction with said shoe for reversing said clutch mechanism at each end of the travel of the shoe, and a plurality of supplemental cord frames adapted to be supported by and moved with the 20 chain carriers, each of said supplemental frames having in its end portions rotatable cord hooks, and a worm on each cord hook for engagement with the adjacent transverse worm screw, for the purpose of causing rotation of the cord hooks during the movement of the supplemental frames through 25 the machine, substantially as described.

2. In a machine of the class described, the combination with a main frame, of a pair of 30 transversely extending worm screws therein, a supplemental frame carrier adjacent to each of said worm screws, means for driving the worm screws in unison, a polishing shoe, abrasive material on its lower surface, a longitudinally extending worm screw, means for 35 rotating the same and for periodically reversing its direction of rotation for the purpose of moving the shoe back and forth in the machine, and a plurality of supplemental 40 cord frames adapted to be supported by and carried with the carriers aforesaid, each of said cord frames having in its end portions worms adapted for engagement with the 45 worm screws aforesaid for rotation thereby, 50 substantially as described.

3. In a machine of the class described, the combination with a main frame, of a plurality of supplemental cord frames, means for carrying said cord frames transversely 55 of the main frame, each cord frame having in its end portions rotatable cord hooks, worms on said cord hooks, worm screws in the main frame adapted for coöperation with the worms on the hooks, means for 60 driving the worm screws in unison, a polish-

ing shoe, abrasive material on its lower face, and means for moving said shoe back and forth periodically, substantially as described.

4. In a machine of the class described, the combination with a main frame, of a plurality of supplemental cord frames, means for moving said cord frames transversely of the main frame, cord hooks in the end portions of the cord frames, means for rotating said cord hooks as the cord frames are moved transversely of the main frame, a polishing shoe, abrasive material on its lower face, and means for moving said polishing shoe back and forth as the supplemental 75 cord frames are moved through the machine, substantially as described.

5. In a machine of the class described, the combination with a main frame, of a plurality of supplemental cord frames, cord hooks rotatably mounted in the end portions of said cord frames, means for moving the cord frames transversely of the main frame, means for rotating the cord hooks during such movement, an abrading device 80 mounted above the cord frames, and means for moving said abrading device back and forth, substantially as described.

6. In a machine of the class described, the combination with a main frame, of a plurality of supplemental cord frames, means for moving said cord frames transversely with respect to the cords, cord hooks in the cord frames, an abrading device mounted above the cord frames, and means for moving said abrading device back and forth during the movement of the cord frames 90 through the machine, substantially as described.

7. In a machine of the class described, the combination of means for supporting a series of cords under tension, means for moving said supporting means transversely of the cords while maintaining them under tension, abrading means for contact with the cords under tension, and means for moving said abrading means lengthwise of the cords while maintaining contact with them, 100 substantially as described.

8. In a machine of the class described, the combination of abrading means, means for moving the same in one direction in one plane, a series of cords lying in another plane parallel to the first mentioned plane and in contact with the abrading means, 115 means for rotating the cords on their own axes, and means for moving said cords in their plane in a direction, transversely of their length while they rotate on their axes, 120 substantially as described.

9. In a machine of the class described, the combination of abrading means, means for moving the same in one direction in one plane, a series of cords lying in another plane parallel to the first mentioned plane 130

and in contact with the abrading means, and means for moving said cords in their plane, and rotating them on their axes, substantially as described.

5 10. In a machine of the class described, the combination of abrading means, means for supporting the same in one plane, a series of cords lying in another plane parallel

to the first mentioned plane, and means for causing a relative movement of the abrading means and the cords so that any point on the abrading surface moves with respect to the cords transversely of their length and for rotating the cords on their own axes, substantially as described.

EDWARD I. FRIEDMAN.
